(57) **CLAIM**

The ornamental design of a strap retainer for a carried bag, as shown and described.

DESCRIPTION

The present application claims priority of U.S. Ser. No. 12/082,124, filed on Apr. 9, 2008, entitled “Retainer for Bag Shoulder Strap”, the contents of which are incorporated into the present application.

FIG. 1 is a perspective view of the present invention;

FIG. 2 is a top view of the present invention;

FIG. 3 is a bottom view of the present invention;

FIG. 4 is a left side view of the present invention;

FIG. 5 is a front view of the present invention; and,

FIG. 6 is a back view of the present invention.

The right side view is a mirror of the left side view shown in FIG. 4.
